UNITED STATES PATENT OFFICE.

ELMER E. COLE, OF BOSTON, MASSACHUSETTS, ASSIGNOR TO COLE & BARTLETT, A COPARTNERSHIP CONSISTING OF ELMER E. COLE AND JOSEPH W. BARTLETT, OF BOSTON, MASSACHUSETTS.

DESIGN FOR A CRUCIFIX OR SIMILAR ARTICLE.

Application filed July 7, 1924. Serial No. 10,080. Term of patent 14 years.

To all whom it may concern:

Be it known that I, ELMER E. COLE, a citizen of the United States, residing at Boston, in the county of Suffolk and State of Massachusetts, have invented a new, original, and ornamental Design for Crucifixes or Similar Articles, of which the following is a specification, reference being had to the accompanying drawing, forming part thereof.

Figure 1 is a plan view of a crucifix showing my new design.

Figure 2 is a side view thereof.

I claim:

The ornamental design for a crucifix or similar article, as shown.

ELMER E. COLE.
